F. W. MARTIN.

AUTOMATIC CLOSING DEVICE FOR FIRE DOORS.
APPLICATION FILED FEB. 2, 1916.

1,258,033.

Patented Mar. 5, 1918.

UNITED STATES PATENT OFFICE.

FREDERICK W. MARTIN, OF NEW YORK, N. Y., ASSIGNOR TO FRANKLIN RAILWAY SUPPLY COMPANY, OF WILMINGTON, DELAWARE, A CORPORATION OF DELAWARE.

AUTOMATIC CLOSING DEVICE FOR FIRE-DOORS.

1,258,033.

Specification of Letters Patent.

Patented Mar. 5, 1918.

Application filed February 2, 1916. Serial No. 75,784.

To all whom it may concern:

Be it known that I, FREDERICK W. MARTIN, of the borough of Manhattan, in the city, county, and State of New York, have invented a certain new and useful Improvement in Automatic Closing Devices for Fire-Doors, of which improvement the following is a specification.

This invention relates to fluid pressure motors for operating certain closures or other devices, and is particularly adapted for use in the opening and closing of fire doors of boiler furnaces, the object being to provide improved means for automatically effecting a positive closing of the fire door within a predetermined interval after the same has been opened, and thereby prevent the fireman from holding the door open for a longer period.

In this fire door apparatus as used on locomotives, the fluid pressure motor for actuating the doors is usually controlled by a valve operated by a pedal device, and it has been the practice of some firemen to hold the foot upon the pedal with the door open a sufficiently long period of time to deliver several shovelfuls of fuel into the furnace. This practice is objectionable, as large drafts of cold air are admitted to the furnace at such times through the wide open door, which tends to cool the fire and chill the water heating surfaces. With my improvement this is positively prevented, as the door will be promptly closed after a predetermined time even though the fireman retains his foot on the pedal.

My present improvement relates more particularly to that type of door operating and closing devices, including a fluid pressure motor, an expansion chamber of a given capacity or volume and having a restricted inlet port to serve as a timing element in which the pressure increases at a certain rate, and valve means operated by a certain pressure in said chamber to cut off the supply of fluid to the motor, whereupon the door may close automatically either by gravity or otherwise. One of the features of my improvement comprises a door motor having a normally open port or passage from the manually operated pedal valve into the cylinder, and an auxiliary valve operated by the pressure in the expansion chamber for closing said port or passage at

a predetermined interval of time after the opening of the pedal valve. Another feature comprises means for automatically returning the auxiliary valve to its normal position with said port or passage open, when the pedal valve is released. These and other objects will now more fully appear from the following detailed description, the features of novelty being set forth in the claims.

In the accompanying drawing, the figure shows, in vertical section, one form of motor and expansion chamber device embodying my improvement, and connected to a pair of fire doors.

My improvement may be applied to various forms of fluid pressure motors and fire doors, but in the drawing I have illustrated the same in connection with a fluid pressure motor comprising a horizontal cylinder, 10, containing a piston, 9, having a pin and link connection with one of the doors, 6, which doors are provided with intermeshing segmental gears, 8, and pivoted to swing laterally and vertically. The doors are opened by admitting fluid under pressure to the working face of the piston, and are normally closed by gravity when said fluid is exhausted to the atmosphere. For this operation a manual valve, such as 13, is provided for controlling the admission of fluid, such as compressed air, from a source of supply, 11, to the inlet port, 15, said valve also controlling the exhaust port, 16.

On locomotive boilers the manual valve is usually operated by a pedal device having an arm, 23, for raising the valve to its open position. According to the usual and proper practice, the fireman steps upon the pedal to raise the valve, and thereby close the exhaust port, and open the admission to supply fluid to the piston to open the doors at the time he delivers a shovelful of coal. He then releases the pedal to close the valve, and open the exhaust port, whereupon the fluid in the cylinder escapes to the atmosphere, and the doors immediately close by gravity. At the time of delivery of the next shovelful, the valve is again raised, and the operation is repeated.

According to this improvement, the passages, 14 and 15, from the manually operated valve, 13, to the cylinder, are normally open, which provides for the free admission of fluid to, and the exhaust of the same from,

the cylinder in the normal operation of the pedal valve to open and close the furnace door. An auxiliary valve device, preferably in the form of a differential piston valve, 32, is provided for closing the port or passage, 15, when the pressure in the expansion chamber reaches a predetermined amount. In the construction, as shown, the differential piston valve is made hollow and mounted in a chamber formed in the cylinder head, and the expansion chamber, 31, comprises the space within the hollow piston valve and the chamber formed in the cap, 30, of the valve chamber. This gives the desired capacity or volume to the expansion chamber which is provided with the restricted inlet port, 33, formed through the smaller head of the hollow differential piston valve, the larger end being subject to the pressure in the expansion chamber. The piston, 32, is provided with a groove, 34, adapted to register with exhaust ports, 35, and 35^a, and open a separate exhaust from the cylinder when actuated by the pressure in the expansion chamber to cut off the admission port, 15. A movable plunger, 36, subject at all times to fluid pressure from the source of supply, 11, is mounted in the upper end of the valve chamber and bears upon the smaller end of the differential piston valve to return the same to its normal position and open the admission port, 15, when the pedal valve is released and the fluid from the expansion chamber escapes to the atmosphere through ports and passages, 33, 14 and 16.

When the valve, 13, is raised by the pedal device, the exhaust port, 16, is closed by the stem of valve, 13, and fluid is admitted through passage, 14, to the valve chamber, where it acts upon the upper or smaller end of the differential piston valve, and through port, 15, into the cylinder, 10, moving the piston, 9, to open the doors. At the same time fluid feeds through the restricted port, 33, into the expansion chamber, 31. If the pedal device be then promptly released, the valve, 13, closes and opens exhaust port, 16, whereupon the fluid from the cylinder and from the expansion chamber escapes to the atmosphere, and the doors close by gravity.

If, however, the pedal device is retained in its open position, with the valve, 13, raised, the pressure continues to increase in the expansion chamber, 31, and, acting on the larger area of the differential piston valve, 32, overcomes the opposing pressure on the smaller area and moves the piston valve upward to close the port, 15, and open the separate exhaust port, 35, at a predetermined interval of time after the opening of the pedal valve. The fluid then escapes from the cylinder, and the doors are promptly closed. The differential piston valve, 32, and plunger, 36, will remain in the

upper position, being held by the pressure in the expansion chamber, until the pedal device is released, and valve, 13, closed, whereupon the pressure will be released from the expansion chamber, and the differential piston valve will be automatically returned to its normal position with port, 15, open, by the movement of the plunger, 36, which is subject to the fluid pressure from the supply pipe, 11.

It is, therefore, apparent that, with my improvement, the fire doors will be automatically closed within a predetermined short interval of time after the opening of the manual valve even though the fireman retains his pedal device open, thereby insuring what is termed "single shovel firing", or the delivery of but one shovelful of fuel into the furnace at each opening of the door.

Having now described my invention, what I claim as new and desire to secure by Letters Patent is:

1. In a fire door apparatus, the combination of a door, a cylinder and piston for operating the door, said cylinder having a normally open admission port, a manually operated valve for controlling the supply of fluid through said port, an expansion chamber, and a valve operated by the pressure in said chamber for automatically closing said port at a predetermined time after the opening of said manual valve.

2. In a fire door apparatus, the combination of a door, a cylinder and piston for operating the door, said cylinder having a normally open admission port and a separate exhaust port, a manually operated valve for controlling the supply of fluid through said admission port, and the exhaust therefrom, an expansion chamber having a restricted inlet port, and a valve operated by the pressure in said chamber for closing the admission port and opening the separate exhaust port from the cylinder at a predetermined time after the opening of the manual valve, thus permitting the closing of the door.

3. In a fire door apparatus, the combination of a door, a cylinder and piston for operating the door, said cylinder having a normally open admission port, a manually operated valve for controlling the supply of fluid through said port, an expansion chamber having a restricted inlet port, and a differential piston valve for controlling said admission port and subject on one side to the pressure in the expansion chamber and on the other side to pressure of fluid admitted through said manual valve.

4. In a fire door apparatus, the combination of a door, a cylinder and piston for operating the door, said cylinder having a normally open admission port, a manually operated valve for controlling the supply of fluid through said port, an expansion cham-

ber, a valve operated by the pressure in said chamber for automatically closing said port at a predetermined time after the opening of said manual valve, and means for automatically returning said valve to open the admission port when the manual valve is released.

5. In a fire door apparatus, the combination of a door, a cylinder and piston for operating the door, said cylinder having a normally open admission port, a manually operated valve for controlling the supply of fluid through said port, an expansion chamber, a valve operated by the pressure in said chamber for automatically closing said port at a predetermined time after the opening of said manual valve, and a fluid pressure actuated plunger for returning said

valve to open said admission port when the manual valve is released. 20

6. In a fire door apparatus, the combination of a door, a cylinder and piston for operating the door, said cylinder having a normally open admission port, a manually operated valve for controlling the supply of 25 fluid through said port, an expansion chamber having a restricted inlet port, a hollow differential piston valve forming a portion of the expansion chamber and operated by the pressure in said chamber to close said admission port at a predetermined time after the opening of the manual valve. 30
